(57) **CLAIM**

The ornamental design for a container lid, as shown and described.

DESCRIPTION

FIG. 1 is a top front right perspective view of our new, original, and ornamental design for a container lid.

FIG. 2 is a front view thereof.

FIG. 3 is a rear view thereof.

FIG. 4 is a left side view thereof, the right side view being a mirror image thereof.

FIG. 5 is a top view thereof.

FIG. 6 is a bottom view thereof.

FIG. 7 is a cross-sectional view thereof taken along line 7-7 in FIG. 2.

FIG. 8 is a top front right perspective view thereof with the lid open.

FIG. 9 is a front view thereof with the lid open.

FIG. 10 is a rear view thereof with the lid open.

FIG. 11 is a left side view thereof with the lid open, the right side view being a mirror image thereof.

FIG. 12 is a top view thereof with the lid open.

FIG. 13 is a bottom view thereof with the lid open; and, FIG. 14 is a cross-sectional view thereof taken along line 14-14 in FIG. 9.

The dashed lines illustrate portions and environment of the container lid that form no part of the claimed design.
